UNITED STATES PATENT OFFICE.

JOHN POWELL, OF KIDDERMINSTER, ENGLAND, ASSIGNEE TO HENRY
JECKS DIXON & SONS, OF SAME PLACE.

DESIGN FOR CARPETS.

Specification forming part of Design No. 6,360, dated January 21, 1873.

To all whom it may concern:

Be it known that I, JOHN POWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This design consists of a lozenge-shaped figure, formed by a grouping of triangles, diamonds, branches, and other ornamental designs around an irregular rectangle. Down the middle of this figure runs another with parallel sides and pointed ends. This figure is ornamented with a number of small designs formed of *fleurs-de-lis* placed between keys. At each end of the rectangle is a large dia-

mond with dark border and center, which diamond also forms the end of the principal figure. At each side of the lozenge are two Egyptian crosses, from the arms of which hang curved ornaments. At each end of the lozenge is an arched figure with dark borders and embellished on the sides with short vines terminating in leaves. At each end of the arch is a multifoil pendant. This arch is connected with one of similar design, but turned in an opposite direction by an ornamental cruciform figure with rounded ends. The interstices between these arches are filled by a small and elaborate ornament.

I claim as my invention—

The design for carpets, as shown.
JOHN POWELL.

Witnesses:

JOHN JEROWLER,
JOHN W. CHADWICK, Kidderminster.
